(57) **CLAIM**

The ornamental design for a slim fingerprint smart lock, as shown and described.

DESCRIPTION

FIG. 1 is a top perspective view of a slim fingerprint smart lock;

FIG. 2 is a front view of the slim fingerprint smart lock;

FIG. 3 is a back view of the slim fingerprint smart lock;

FIG. 4 is a left side view of the slim fingerprint smart lock;

FIG. 5 is a right side view of the slim fingerprint smart lock;

FIG. 6 is a top view of the slim fingerprint smart lock; and,

FIG. 8 is a bottom perspective view of the slim fingerprint smart lock.

The broken lines shown in the drawings are included for illustration purpose only and form no part of the claimed design.
